EXPANSIBLE WOVEN TUBING

Harry E. Thompson, Providence, R. I., assignor to
 Anaconda Wire & Cable Company, New York,
 N. Y., a corporation of Delaware

Application June 2, 1934, Serial No. 728,805

3 Claims. (Cl. 137—90)

This invention relates to improvements in woven tubing characterized particularly by the inclusion of a filling strand by resilient material, such as a rubber thread-like member either with or without a covering of yarn.

5 The invention will be apparent from the following detailed disclosure when read in connection with the accompanying drawing and will be defined with particularity in the appended claims.

10 In the drawing—

Fig. 1 is a view partly in elevation and partly in section, the thickness of the parts being somewhat exaggerated in the interest of clear illustration; Fig. 2 is a detail view on an exaggerated scale of a filling strand such as used in tubing in one embodiment of the invention; Fig. 3 is a view similar to Fig. 1, illustrating a modification; Fig. 4 illustrates the application of the invention.

15 The woven tubing of the present invention includes interwoven warp and filling strands, the warp strands being of cotton or other suitable fibrous material. Interwoven with the filling strands, there is a strand having greater elasticity than the fibrous strands usually employed in woven tubings. For example, the tubing includes longitudinally extending warp strands 10 of cotton, interwoven with helical filling strands 12, such as shown in Fig. 2. The filling strands 12 in this embodiment include an elastic member 14 of rubber or extruded filamentary body of latex, covered with an outer layer or yarn, such as indicated at 16. In some cases, instead of covering the filling thread with yarn, I may employ a plain elastic strand of rubber, as indicated 20 at 18 in Fig. 3, which helical filling strand will be interwoven with a fibrous cotton or other fibrous strands 10'. In both forms of the invention, the tube will preferably be provided with an interior coating 20 of rubber. This rubber may 25 be the residue of an aqueous dispersion of latex. The tubing may also be treated with asphalt, pitches and the like and may be coated either inside or outside with lacquer. The tubing of my invention, which includes as an essential element 30 the elastic filling strand, will be expansible radially. This expansibility of the tubing is advantageous because it enables me to stretch the same to a limited extent so that it can be snugly engaged, for example, with a fitting 22, such as 35 indicated in Fig. 4.

40 The elasticity of the filling strand will tend to hold the tubing in firm engagement with the fitting. And because the tubing is formed of interwoven fibrous and elastic strands the same will

45 resist tearing and its life will exceed that of all rubber tubes, in which it is well known that, when the same are expanded and stretched over fittings, they are short lived. The tubing of my invention while not limited thereto is well suited for use in windshield wiper installations for motor vehicles and the same can be readily snugly engaged with metal fittings, so as to prevent air leakage or loss of vacuum.

50 The inner rubber coating or lining, it will be understood forms an impervious layer which fills or seals the interstices between the warp and filling strands.

55 The elastic filling strands, whether yarn covered or plain, it will be understood permit the tube to be expanded in a radial direction. The adjacent convolutions of the helical filling strand are substantially circular in the finished tube while the fibrous warp strands are substantially straight and parallel with the axis of the tube. 60 This relationship is deemed important because the warp strands are capable of withstanding considerable tension without having a tendency to reduce the diameter of the tube. My combined elastic and fibrous tube distinguishes from an ordinary rubber tube, in which it is known that a tension tends to constrict the same and reduce its internal diameter.

65 While the invention has been described with particular reference to the embodiments illustrated, it is intended that the drawing and description are to be interpreted in an illustrative rather than a limiting sense.

What I claim is:—

70 1. An expansible tubing of the character described comprising interconnected fibrous and elastic strands bonded to an impervious internal coating so that the structure of the tube as a whole is expansible and contractible.

75 2. An expansible tubing of the character described comprising longitudinally extending fibrous warp strands interwoven with helical filling strands of rubber covered with cotton yarn, said interconnected strands being united with an interior coating of rubber so that the tube 80 structure is expansible and contractible.

85 3. An expansible and contractible woven tubing including cotton warp strands interwoven with helical filling strands of rubber and a coating of rubber bonded to such interwoven warp 90 and filling strands forming an impervious layer which fills or seals the interstices between the warp and filling strands.
